UNITED STATES PATENT OFFICE.

JULIUS WEINBERGER, OF NEW YORK, N. Y., ASSIGNOR TO RADIO CORPORATION OF AMERICA, A CORPORATION OF DELAWARE.

RADIO SIGNALING SYSTEM.

Application filed October 11, 1921. Serial No. 507,103.

To all whom it may concern:

Be it known that I, JULIUS WEINBERGER, a citizen of the United States, residing in the borough of Manhattan, city, county, and State of New York, have invented certain new and useful Improvements in Radio Signaling Systems, of which the following is a specification.

This invention relates to transmitting systems for radio signaling and particularly to a method of and an arrangement for controlling the amplitude of high frequency signaling currents. The invention is applicable to radio telegraphic or radio telephone transmitters, but for purposes of illustration the invention will be particularly described with reference to radio telephonic modulation as it is particularly suitable for this purpose.

20 In accordance with one aspect of the invention the amplitude of the high frequency current is varied by means of an arrangement in which the variation of a low frequency magnetization circuit having an iron core cooperates with a high frequency winding on the core to greatly vary the effective resistance of the latter. The change in the resistance of the high frequency winding is due to the change of the iron losses of the core when the direct current magnetization is varied. With the former types of ferromagnetic modulator a change in inductance occurs and this phenomenon has heretofore been used to cause modulation of the radiated energy due to the detuning effect. The present arrangement varies the inductance to some extent, but is utilized under conditions where the change of the iron losses is the controlling factor. This condition is most readily realized at high frequencies (300,000 cycles or more) at which frequency I have found that the resistance variation in its effect on the antenna current is large compared with the inductance variation, while with low frequencies the reverse condition would normally tend to prevail. In order that the resistance variation may be effective for modulating without appreciable modulation by inductance variation or detuning, the ratio of total inductance to the change of inductance should be high and the ratio of the total resistance to the change of resistance should be low. These conditions occur in the arrangement de-

scribed, particularly at the high frequencies 65 usual in radio telephonic transmission.

In accordance with another aspect of the invention a vacuum tube oscillator is used for supplying high frequency energy to the antenna and the antenna current supplied 60 thereby is modulated without substantial detuning by means of a ferromagnetic device and a telephone connected with the antenna so as to vary the effective resistance of the antenna. By this means a larger 65 current can be modulated by resistance changes than when an ordinary microphone in the antenna is used for this purpose. I have discovered that with the ferromagnetic modulator the resistance of the high frequency circuit may be varied by means of such small direct current variations as are obtainable with an ordinary microphone or telephone transmitter. I have further discovered that it is possible by proper selection of the turns of the high frequency and 70 low frequency windings and the dimensions of the core to produce this variation of resistance at frequencies corresponding to relatively short wave lengths (1,000 meters 75 or less) while producing only variations in the inductance of the high frequency winding which are ineffective for modulation or detuning. Modulation by resistance in the manner described is especially advantageous 80 because the radiation of interfering frequencies is eliminated and the radiation is practically limited to the desired frequency.

75 In the drawings:

Fig. 1 is a diagrammatic illustration of 90 a radio telephone transmitter in accordance with the invention.

Fig. 2 is a set of curves illustrating the operating characteristics of the apparatus.

In Fig. 1 reference character 1 designates 95 the antenna grounded at 2. A high frequency oscillation generator 3 is coupled to the antenna by means of a high frequency transformer having its primary coil 4 in the generator circuit and its secondary coil 5 100 in the antenna circuit. Although various types of oscillation generators may be utilized I have illustrated an especially simple and desirable form for an amateur radio telephone comprising one or more three-electrode vacuum tubes having the filament 6 connected to the plate 6' through a source of 105 E. M. F. 7 shunted by a condenser 7' to by

pass radio frequencies. The primary coil 4 is connected between the generator and plate and a coil 8 connected to the grid and filament is coupled to the primary coil 4.

5 The controlling arrangement for varying the amplitude of the oscillations comprises a winding in the aerial wound on an iron core, a second winding on the core connected to the signaling means and source of direct 10 current for magnetizing the core. In the illustration the high frequency winding consists of two coils 8, 9, wound on separate laminated iron cores 10, 11, in the same direction connected in series in the ground connection 15 of the antenna. The direct current winding consists of two coils 12, 13 wound in opposite directions on the iron cores and connected in series through a battery 14 and an ordinary microphone telephone transmitter 20 15.

The use of the vacuum tube oscillator without a modulating means connected thereto enables the operation and the circuits to be greatly simplified. Modulating 25 tubes which complicate the circuits and increase the initial cost and upkeep are eliminated as well as numerous circuit elements which are required when modulating tubes are used. The change of resistance of the 30 magnetic modulator is used to directly affect the antenna current.

The two cores in the modulator circuit with direct current windings in opposite directions are used to prevent the variations 35 in the antenna current from inducing similar changes in the direct current winding. The invention however is not necessarily limited thereto.

For purposes of illustration in Fig. 2 the 40 operating characteristics of the system shown are illustrated with a hollow rectangular iron core 4 cm. wide and 5.3 cm. long outside dimensions, with arms 1.4 cm. wide and built up of 25 pieces of laminated sheet iron (.05-.01 cm. thick). The direct current winding consists of 100 turns on each core 45 wound in opposite directions connected to a battery of six volts and a microphone. With a microphone through which .4 ampere flows this gives 40 ampere turns per core under normal conditions. Supposing that the microphone used will cause the direct current to vary at audible frequencies between .1 and .6 ampere, the direct current 50 magnetization will vary from 10 to 60 ampere turns and the effective resistance as shown on Fig. 2 will vary between values of approximately 17 ohms and 7 ohms for a normal radio frequency current of two amperes.

If such a modulator is placed in the antenna circuit of a tube transmitter, as shown in Fig. 1, the phenomena which occur are rather complex. As the microphone or mag- 65 netization current is varied, the modulator

tends to vary its resistance due to change of eddy current losses; but a variation in the resistance of the antenna circuit causes a drop in the output of the tube since the antenna circuit then no longer fits the plate 70 coupling adjustment necessary to adapt it into the tube plate circuit. The antenna current therefore goes down more rapidly than it would, were the output of the tube to remain constant; however, when the antenna current goes down, it will be seen from Figure 2 that the resistance of the modulator for a given number of magnetizing D. C. ampere turns its lower with lower radio 80 frequency currents. On the whole, therefore, the modulator resistance does not vary as much as it would, were the antenna current to remain constant. A net variation in antenna current does, however, occur as the microphone current varies, and by a suitable adjustment of coupling coils 4 and 5, substantially complete modulation of the antenna current can be obtained. Under these conditions the variation of inductance due to the variation of the direct current magnetization is for example, from 1 microhenry to .2 microhenry, which variation is substantially of the same order on long as well as short wave lengths although the resistance variation proportionally is smaller 95 for long wave lengths, as it varies directly with the frequency. With short wave lengths (1000 m.) the antenna and loading inductance used will be in the neighborhood of 100 microhenries and the variation of .8 microhenry will be practically ineffective in producing modulation by detuning. From this explanation it will be apparent that the modulation by the magnetic modulator in accordance with the invention is accomplished by varying the resistance without substantial detuning, whereas a magnetic modulator ordinarily acts as a variable inductance for detuning the antenna.

Having described my invention, what I 110 claim is:

1. In radio signaling with a ferromagnetic modulator and a high frequency generator the method which consists in generating high frequency signaling currents, producing variations in the magnetization of said modulator and modulating said high frequency signaling currents in accordance with the variations of the iron losses of the modulator when its magnetization is varied 115 while maintaining the inductance of said modulator substantially constant with respect to the inductance of the circuit in which it is placed.

2. In radio signaling with a ferromagnetic modulator having a high frequency circuit and a magnetizing winding, the method which consists in supplying high frequency signaling currents to said high frequency circuit, producing variations in 130

the magnetization of said modulator and causing said variations to modulate said signaling currents in accordance with changes in the resistance of the high frequency circuit produced by changes in the iron losses in the modulator when its magnetization is varied while maintaining the inductance of said modulator substantially constant with respect to the inductance of said high frequency circuit.

3. In radio telephony with a ferromagnetic modulator having a high frequency circuit and a magnetizing winding associated with a microphone, the method which consists in supplying high frequency signaling currents to said high frequency circuit, producing variations in the magnetization of said modulator in accordance with the microphone currents and causing said variations to modulate said signaling currents at speech frequencies in accordance with changes in the resistance of the high frequency winding produced by changes in the eddy current losses in the modulator when its magnetization is varied while maintaining the inductance of said high frequency circuit substantially constant.

4. In radio signaling with a ferromagnetic modulator having a high frequency circuit and a magnetizing winding, the method which consists in producing variations in the magnetization of said modulator, and supplying currents to said high frequency winding at a frequency sufficiently high to cause the amplitude of the high frequency current to be modulated in accordance with the variations of resistance of the high frequency winding due to the iron losses of the modulator while maintaining the inductance of said high frequency circuit substantially constant.

5. In radio signaling with a ferromagnetic modulator having a high frequency winding in a tuned oscillation circuit and a magnetizing winding, the method which consists in producing variations in the magnetization of said modulator and generating currents in said tuned oscillation circuit at a frequency sufficiently high to cause the amplitude of the high frequency current to be modulated in accordance with the variations of resistance of the high frequency

winding due to the iron losses of the modulator while maintaining the tuning of said oscillation circuit substantially constant.

55

6. In radio signaling with a ferromagnetic modulator having a circuit comprising a high frequency winding connected in an antenna, and a magnetizing winding, the method which consists in producing variations in the magnetization of said modulator, generating high frequency currents in said circuit and causing said variation of magnetization to change the effective resistance of said winding to a large extent and to maintain the effective inductance of said winding substantially constant.

60

7. In a radio transmitting system the combination of an antenna circuit comprising a coil, a high frequency generator, signaling means, a source of current connected to said signaling means and means for varying the effective resistance of said coil while maintaining the effective inductance relatively constant for the high frequency currents, said last mentioned means comprising an iron core and a winding and said winding being associated with said source of current and signaling means.

70

8. In a radio transmitting system, the combination of an antenna circuit comprising a coil, a three-electrode vacuum tube high frequency generator, signaling means, a battery connected thereto and means for varying the effective resistance of said coil while maintaining the effective inductance thereof relatively constant for the high frequency currents, said last mentioned means comprising an iron core and a winding, said winding being associated with the signaling means.

80

9. In a radio telephone transmitting system, the combination of an antenna, a three electrode vacuum tube high frequency generator, a battery, a microphone connected to the battery and means for varying the effective resistance of said antenna and maintaining the effective inductance relatively constant for high frequency currents, said last mentioned means comprising an iron core and a pair of windings, one of said windings being associated with the antenna and the other winding with the microphone.
